(57) **CLAIM**

The ornamental design for a cable gland, as shown.

DESCRIPTION

FIG. 1 is a perspective view of a cable gland showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top view thereof;

FIG. 7 is a bottom view thereof;

FIG. 8 is a perspective view of a mating part of the cable gland shown in FIG. 1;

FIG. 9 is a front elevation view of the mating part shown in FIG. 8;

FIG. 10 is a rear elevation view of the mating part shown in FIG. 8;

FIG. 11 is a left side view of the mating part shown in FIG. 8;

FIG. 12 is a right side view of the mating part shown in FIG. 8;

FIG. 13 is a top view of the mating part shown in FIG. 8; and, FIG. 14 is a bottom view of the mating part shown in FIG. 8. The broken line showing of the cable gland represents unclaimed subject matter and forms no part of the claimed design.
